(No Model.)

F. D. OWEN.
PEDAL FOR BICYCLES.

No. 553,685.

Patented Jan. 28, 1896.

UNITED STATES PATENT OFFICE.

FREDERICK D. OWEN, OF WASHINGTON, DISTRICT OF COLUMBIA.

PEDAL FOR BICYCLES.

SPECIFICATION forming part of Letters Patent No. 553,685, dated January 28, 1896.

Application filed July 22, 1895. Serial No. 556,797. (No model.)

To all whom it may concern:

Be it known that I, FREDERICK D. OWEN, a citizen of the United States, residing at Washington, in the District of Columbia, 5 have invented certain new and useful Improvements in Pedals for Bicycles; and I do hereby declare the following to be a full, clear, and exact description of the invention, such as will enable others skilled in the art to which 10 it appertains to make and use the same.

My invention relates to certain new and useful improvements in pedals for bicycles, and has for its object a construction which will rigidly bind the foot to the pedal-base 15 during the pedaling operation, but which will instantly release the foot at the will of the rider or in the event of his being thrown from the machine.

In the accompanying drawings, illustrative 20 of my invention, Figure 1 represents a plan view of one form of bicycle-pedal embodying my invention, certain of the parts being shown in section and the position of certain others indicated in dotted lines. Fig. 2 represents 25 a section and partial elevation on the line 2 2 of Fig. 1. Fig. 3 represents a top plan view thereof partly in section with the pedal-plate and binding accessories removed. Fig. 4 represents a section on the line 4 4 of Fig. 1. 30 Fig. 5 represents certain details of construction. Fig. 6 represents a top plan view of a modified form of pedaling-plate, and Fig. 7 represents a top plan view of another modification.

Similar letters of reference indicate similar parts throughout the several views.

Referring to the drawings, A indicates the crank-arm of a bicycle-pedal provided with a pedal-supporting arm *a*, having at its outer 40 end the usual cone *b*, nut *c*, and intermediate washer *d*, said cone *b* and the extended end *a'* of the arm *a* being cut away at their proximate edges so as to form a track for the bearing-balls *e*. The ball-bearing is completed by 45 a steel forging *f* milled out to accommodate the balls *e*, and the ball-bearing thus made is rendered dust-proof by the interposition on opposite sides of the series of balls of two annular disks *g* of felt or the like. The forging 50 *f* is provided with a forward extension *f'* and a lug *f''*. A pivot-pin *h*, at right angles to the horizontal axis of vertical oscillation of

the pedal, is provided at its upper end with an expanded head *h'* and at its lower end with a screw-thread *h''*. The pivot-pin *h* serves as 55 the means of connection between the forging *f* and the pedal-plate *m*, and is secured in place by the conical nut *h³* and set-nut *h⁴* with the intermediate washer *h⁵*, these nuts being adjustable so as to take up wear. 60 Through the instrumentality of the pivot-pin the plate *m* is permitted to have a slight oscillating motion either upon the pivot-pin or with it and in a plane at right angles to its plane of vertical oscillation. 65

The pedal-plate *m* is preferably made of sheet-steel struck up in a suitable die so as to provide a track for the bearing-balls *e'*. In some instances the plate *m* is provided with an additional trackway at its rear end for the 70 reception of bearing-balls *e²*, thereby still further diminishing friction. The forging *f* is provided on its upper surface with corresponding tracks for the reception of the bearing-balls, as indicated. 75

The pedal-plate *m* may extend rearwardly, as indicated in dotted lines, to form a support for the heel of the rider; but preferably it terminates at a point in advance of the heel and is provided thereat with an upwardly-projecting curved ridge *n* serrated upon its upper edge. The pivot-pin *h* in practice will be found to be located, in the position shown, about midway beneath the ball of the foot, and will furnish a center or sidewise oscillation so as to accommodate itself to the slight sidewise oscillation of the foot during the 85 pedaling action.

At its forward end the plate *m* is provided with a projection *m'*, through which passes a 90 pivot-pin *r*. This pivot-pin is screw-threaded at its lower end for the reception of a retaining-nut *r'* and serves as a center of oscillation for two pivoted members *s* *s'*, which extend outwardly in bow form with a return-bend, as shown more fully in Fig. 2. These arms constitute means for automatically binding or gripping the foot to the pedal-plate. Thus, for instance, the arm *s'* extends 95 with an upward bend *s²* through a slot *m²* of the pedal-plate, and the arm *s* is provided with an upturned portion *s³* engaging with a plate *s⁴* which is connected to the pedal-plate *m* by means of a sliding pin *s⁵*. During the 100

pedaling action the toe portion of the rider's shoe naturally presses forward between the arms s s' and forces said arms apart. Consequently the inner ends of said arms move 5 toward each other and clamp the rider's shoe between the projections s^2 and s^4 . When the rider wishes to release his foot he moves it backwardly, thereby taking the pressure from the forward ends of the arms s s' , and 10 consequently relieving the binding action of the clamping ends upon the shoe.

The advantage of using simply an upturned end s^2 as a clamping member for the shoe is one of economy of construction, and it is of 15 course obvious that the same upturned arm could be used as the clamping member of the arm s . The advantage of using the plate s^4 is that it may be made adjustable so that the pedal may be set for any particular width of 20 shoe, and it is equally evident that this adjustable plate may be used as the clamping member of the arm s' , so as to give a wider range of adjustment.

In the construction shown in Fig. 6 I have 25 substituted for the plate m two homologous plates m^5 m^6 , having arms s^5 s^6 bowed or curved in a manner similar to the curvature of the forward ends of the arms s s' . These plates are provided with a series of apertures t t' t^2 .

30 According as the pivot-pin h is passed through the one or the other of this series of apertures the clamping leverage of the arms s^5 s^6 is correspondingly adjusted. The plates m^5 m^6 are provided with upturned clamping portions s^7 35 s^8 , which may be adjusted by means of the pin-and-slot connection s^9 . The operation of this modification of the invention is apparent. The pedal-plate, consisting of the two sections m^5 m^6 , is connected to the forging f by means 40 of the pivot-pin h and constitutes its own clamping device for the shoe of the rider—i. e., the forward pressure of the toe of the rider's shoe between the bowed arms s^5 s^6 causes the plate-sections m^5 m^6 to come together, thereby clamping the edge of the shoe 45 between the projections s^7 s^8 .

In the modification shown in Fig. 7 the plate m , secured to the forging f in the same manner as is represented in Figs. 1 and 2, is provided upon its upper surface with slide-plates v v' , pivoted to each other at v^2 and connected to the plate m by slots v^3 and pins v^4 . At their forward ends the plates v v' are adapted to have secured to them the curved arms s^{10} s^{11} , 55 bowed or arched in like manner to that shown in Fig. 2. These arms are adjustable by means of bolt-nuts v^5 entering in one of a series of corresponding perforations in the plates v v' . At their rear ends the plates v v' are provided 60 with clamping projections s^{12} s^{13} . In this modification of the invention the foot of the rider during the pedaling operation causes the plates v v' to move bodily forward, and this movement being guided by the pin-and-slot 65 connection with the plate m causes the clamping projections s^{12} s^{13} to bind upon the edge of

the rider's shoe. A backward movement of the foot releases this clamping action.

So far as I am aware it is broadly new to provide a bicycle-pedal with shoe-clamps 70 which are caused to move inwardly and automatically bind the shoe to the pedal by reason of the forward thrust of the shoe during the pedaling action, and which are adapted to be disengaged at the will of the operator by the 75 withdrawal of the shoe. This is the main characteristic feature of my invention illustrated in the several modifications, and is of a generic character common to them all. I desire to be understood therefore as claiming this feature 80 broadly wherever found in bicycle-pedals.

It will be of course understood that the automatic clamping devices, as hereinbefore described, are applicable to the ordinary form of rectangular pedal having two bearings in 85 use at present. In fact, the claims are intended to cover the devices therein set forth wherever they may appear in bicycle-pedal construction. I may also in some instances dispense with the automatic clamping devices 90 shown in Figs. 1 and 2 and use the pedal construction therein illustrated without said clamping devices, in which event I would still derive the useful function due to the foot-plate pivoted in advance or to one side of the 95 axis of the pedal-shaft.

Of course it is evident that rubber can be applied to this form of pedal, as may be found expedient.

Having thus described my invention, what 100 I claim, and desire to secure by Letters Patent, is—

1. A bicycle pedal provided with foot clamps, having operating members pivoted together and adapted to be spread by the 105 rider's shoe during pedaling and to thereby cause the foot-clamps to bind upon the shoe; substantially as described.

2. A bicycle pedal provided with foot clamps, and means in the path of forward 110 pressure of the rider's shoe for causing said clamps to move inwardly and bind upon the pedal base to oscillate sidewise; substantially as described.

3. A bicycle pedal mounted to swing in a vertical plane upon an axial support, and provided with foot clamps mounted to swing sidewise upon pivotal bearings located in advance of the axial support and provided with forward projections beyond the pivotal mounting, for engagement with the toe portion of the rider's shoe; substantially as described.

4. A bicycle pedal mounted to swing in a vertical plane upon an axial support, and provided with a base piece, a foot plate pivoted to swing side-wise upon the base piece and having shoe clamping projections and arms pivoted in advance of the axial support and having projections beyond the pivotal mounting for engagement with the toe portion of the rider's shoe; substantially as described.

5. A bicycle pedal mounted to swing in a vertical plane on an axial support, and provided with a base piece, a foot-plate pivoted to swing sidewise upon the base-piece and having shoe clamping projections, ball-bearings interposed between the base-piece and foot-plate, arms pivoted in advance of the axial support and having projections beyond the pivotal mounting for engagement with the toe portion of the rider's shoe; substantially as described.

6. A bicycle pedal, provided with a foot plate mounted to swing laterally upon a cen-

ter in advance of the axis upon which the pedal is mounted; substantially as described. 15

7. A bicycle pedal, provided with a foot plate mounted to swing laterally upon a center in advance of the axis upon which the pedal is mounted, and ball bearings for said foot plate; substantially as described. 20

In testimony whereof I affix my signature in presence of two witnesses.

FREDERICK D. OWEN.
